US00D909574S

(12) **United States Design Patent** (10) Patent No.: **US D909,574 S**
(45) Date of Patent: ** Feb. 2, 2021

(54) **HOLDER OF MEDICAL ADHESIVE
DELIVER APPARATUS**

(71) Applicant: **GeneJet Biotech Co., Ltd.**, Taipei (TW)

(72) Inventors: **Fa-Ter Chu**, Taipei (TW); **Ing-Yuan Lin**, New Taipei (TW); **Wen-Yang Lin**, New Taipei (TW); **Chin-Yu Weng**, Chiayi County (TW); **Ming-En Sheen**, Keelung (TW)

(73) Assignee: **GENEJET BIOTECH CO., LTD.**, Taipei (TW)

(**) Term: **15 Years**

(21) Appl. No.: **29/716,975**

(22) Filed: **Dec. 13, 2019**

(51) LOC (13) Cl. **24-02**

(52) U.S. Cl.

USPC **D24/133**

(57) **CLAIM**

The ornamental design for a holder of medical adhesive deliver apparatus, substantially as shown and described.

DESCRIPTION

FIG. 1 is a top, front, and left side perspective view of a holder of medical adhesive deliver apparatus showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom, rear, and right side perspective view thereof.

The broken lines in all views are for the purpose of illustration and are not part of the claimed design.

1 Claim, 8 Drawing Sheets
